GLASS PARTICLE DISPENSING DEVICE

Ralph K. Ready, Saginaw, Mich.

Application November 9, 1946, Serial No. 709,013

3 Claims. (Cl. 275—2)

1

This invention relates to dispensing vehicles or devices, and in particular to vehicles or devices for dispensing finely divided materials, such as glass or plastic particles.

One object of this invention is to provide a dispensing vehicle or device for particles of glass or similar material, such as plastic, particularly for dispensing the tiny light-reflecting glass spheres which are used to designate the center line of a street or highway either by day or by night.

Another object is to provide a dispensing vehicle or device, as set forth in the preceding objects, which will dispense the particles in a band of even thickness and width.

Another object is to provide a dispensing vehicle or device, as set forth in the preceding objects, wherein the particles are supplied to the vehicle or device from a tank and are discharged from the device over the edge of a barrier so that they flow over the barrier like water over a dam or waterfall, and thereby are smoothly and evenly distributed upon the street or highway.

Another object is to provide a dispensing vehicle or device, as set forth in the preceding objects, wherein the distributor or feeder of the device is driven from the wheels upon which the device rolls and controlled by a clutch so that the distribution is accomplished smoothly and evenly regardless of the speed at which the device is moved and can be started or stopped whenever desired and maintained in synchronism with the paint-spraying device with which it is used.

Another object is to provide a dispensing vehicle or device, as set forth in the preceding objects, wherein the device is provided with a swinging spout adjacent the outlet thereof so as to guide the particles as they fall downward toward the highway, yet at the same time, provide a spout which will swing out of the way if it encounters obstacles or irregularities in the highway.

Other objects and advantages of the invention will become apparent during the course of the following description of the accompanying drawings, wherein:

Figure 1 is a top plan view of a glass particle dispensing vehicle and device according to a preferred form of the invention with certain portions broken away to disclose the internal construction more clearly; and

Figure 2 is a vertical section taken along the line 2—2 in Figure 1.

Referring to the drawings in detail, Figure 1 shows a dispensing vehicle, generally designated 10, including as a part thereof an improved dispensing device for dispensing glass particles or

2

the like, generally designated 11, according to a preferred form of the invention. The dispensing vehicle 10 and device 11 are particularly well adapted to the depositing of bands of tiny glass bead-like spheres upon the painted band which divides traffic lanes upon a street or highway, these particles being deposited upon a band of wet paint which has just been sprayed upon the pavement and with which the operation of the present device is synchronized. These tiny glass particles, when illuminated by the vehicle headlights at night, become auto-reflecting and thereby clearly indicate the division between traffic lanes on the highway.

15 Hitherto, it has been very difficult to deposit and distribute glass particles upon such a paint band or line, in an even layer and without scattering the particles widely over the pavement. It has also been difficult to regulate the feeding speed of the particles so that the thickness of the layer can be regulated to suit the speed at which the layer is being deposited. By the present invention, however, the particles are deposited evenly in a band, the thickness of which can be accurately regulated and adjusted to conform to the speed of travel of the device over the highway. The depositing can be started or stopped instantly when desired, and synchronized with the paint spraying device, such as by a clutch 30 which starts and stops both devices simultaneously.

25 The glass particle dispensing vehicle 10 includes an angle member 12 of L-shaped cross-section to which the dispensing device 11 is connected, and having its lower flange 13 secured as by welding to an axle 14. Also secured to the flange 13 as by welding are the ends 15 of a Y-shaped or bifurcated shaft 16. The shaft 16 at its forward end is connected in any conventional manner such as by a ball hitch (not shown) to a truck (not shown) behind which it is towed and which carries a paint spraying device to spray the band upon the roadway and also a tank or reservoir containing the glass particles to be deposited upon the roadway on top of the wet paint. The glass particles flow by gravity to the dispensing device 11 through a flexible pipe of rubber or other suitable material as described in greater detail below.

35 Loosely and rotatably mounted on the outer ends of the axle 14 are the hubs 17 of wheels 18 having tires 19 engaging the roadway. The wheel hubs 17 engage annular abutments or enlargements 20 on their inner sides and are held in position by discs 21 bolted as at 22 to the ends

of the axle 14. Any suitable wheel and axle construction may obviously be used, the one shown in Figure 1 being simplified for clearness of showing.

One of the wheel hubs 17 carries a sprocket 23 which is drivingly connected to a sprocket 24 by an endless sprocket chain 25 encircling both sprockets. The sprocket 24 is loosely and rotatably mounted upon the reduced diameter 26 of a shaft 27 and held thereon by a collar 28 pinned or otherwise secured thereto, as at 29. The hub of the sprocket 24 is provided with axially projecting teeth 30 which are adapted to mesh with corresponding teeth 31 upon a collar 32 forming a part of a crown clutch 33. The collar 32 is keyed or splined as at 34 to the shaft 27 so as to be slidably axially thereon and is provided with an annular groove 35 engaged by inwardly projecting pins 36 (Figure 2) upon the ends of a yoke portion 37 upon the outer end of a shifting lever 38. The latter is pivotally mounted upon a pivot bolt 39 threaded into an angle bracket 40 which in turn is secured as by welding to the vertical flange 41 of the angle member 11. Accordingly, by shifting the lever 38 to and fro, the crown clutch 33 may drivingly connect the sprocket 24 and accordingly the wheels 18 to the shaft 27 or disconnect these elements as desired.

The shifting lever 38 has been illustrated, for simplicity of showing, as a hand lever. In actual practice, however, the lever 38 is shifted by a pneumatic or hydraulic shifter, the action of which is synchronized with the operation of the paint spray gun (not shown). In this manner the feeding of the glass particles is caused to take place only when the paint spray gun is spraying paint, and ceases instantly when spray painting is terminated. In actual practice, also, three glass particle dispensing devices 11 are customarily arranged approximately side by side on the angle member 12 to correspond with the three paint spray guns commonly used. These three paint guns are employed to paint the three bands commonly used for dividing traffic lanes. Ordinarily, only one or two bands are sprayed at one time, a white band being sprayed to divide traffic lanes on a straight-away portion of the road. In places where the view of the road ahead is restricted or obstructed, however, a colored band is added on one side or the other side of the white band to indicate such places where passing is prohibited, the side on which the colored band is located depending upon the direction of traffic. Since one glass particle dispensing device 11 sufficiently illustrates the principles of the invention and simplifies the showing, one only of such devices is shown in the drawing.

Bolted as at 42 to the vertical web 41 of the angle member 12 is a bar 43 to which is welded or otherwise secured an approximately cylindrical drum 44, the ends of which are closed by disc-like end plates 45 secured therein by fasteners 46. The end plates 45 are provided with aligned bores 47 in which the opposite ends of the shaft 27 are journaled. Mounted on the shaft 27 adjacent the inner walls of the end plates 45 are sealing rings 48 of rubber or rubber-like material for the purpose of excluding pieces of the glass particles from the bearing bores 47. The latter have been shown as plain bearings for purposes of simplification whereas in practice sleeve bearings or anti-friction bearings would be used because of their higher efficiency and renewability.

Inwardly of the sealing rings 48 the shaft 27 is enlarged as at 49 and is provided with a pair

of spaced star-plates 50 which serve as spiders to carry elongated approximately rectangular feeding blades 51 extending therebetween and secured thereto as by welding. The upper side 5 of the drum or casing 44 is provided with an inlet port 52 which has welded to it an inlet pipe 53 which extends inside a flexible pipe 54 leading to the tank on the truck (not shown) containing the glass particles to be deposited, the latter being 10 secured thereto by a clamping ring 54a (Figure 2).

Along its rearward end, the drum or casing 44 is provided with an elongated outlet port 55 (Figure 2) upon approximately the same horizontal 15 level as the shaft 27. Extending upward and outward in an inclined direction from the lower edge of the outlet port 55 is a barrier 56, the upper edge 57 of which is above the level of the axis of the shaft 27 so that the barrier 56 serves 20 as a dam over which the glass particles spill in a manner resembling water flowing over a waterfall. The opposite ends of the barrier 56 are connected to the casing 44 by end portions 58. In order to regulate the thickness of the layer of 25 glass particles deposited upon the highway, and also to regulate the feeding rate thereof, a movable slide 59 of approximately L-shaped cross-section is mounted above the barrier 56 and secured to the casing 44 by fasteners 60 extending 30 through slots 61 therein. By loosening the fasteners 60 the slide 59 may be moved up or down so as to widen or narrow the gap between it and the edge 57 of the barrier 56.

In order to guide the glass particles in their 35 descent to the highway, a movable spout 62 is pivotally mounted on the side portions 58 of the barrier 56 by means of pivot screws 63 threaded therein. The spout 62 has open ends 64 and 65, its side walls tapering toward the lower end 65. Extending forwardly from the forward side wall of the spout 62 is a lug 66 serving as an anchorage 40 for one end of a coil spring 67, the opposite end of which is anchored to a lug 68 on the lower side of the drum or casing 44.

In operation, the dispensing vehicle is connected to the towing truck by any suitable connection, such as a ball hitch on the shaft 16 and the flexible pipe 54 is connected to the tank on the truck which holds the glass particles. These 45 glass particles are tiny spheres resembling beads without holes. Due to their smoothness and roundness, they flow by gravity from the tank down through the pipe 54 into the casing or drum 44. The operator starts the truck and dispensing 50 vehicle in motion and operates the controls which start the spray gun in operation to spray paint the ribbon or band on the roadway. At the same time, he shifts the lever 38 to engage the crown clutch 33, causing the rotor within the casing 44 to rotate on its shaft 27, which is driven 55 from the hub of the wheel 18 through the sprocket chain 25 and sprockets 23 and 24.

As the blades 51 rotate around the shaft 27 or, 60 more specifically, its enlarged portion 49, the glass particles in the lower part of the casing 44 are pushed upward through the port 55 (Figure 2) and out through the gap between the end 57 of the barrier 56 and the slide 59. The glass particles 65 spill over the barrier edge 57 like water over a waterfall, and because of their smoothness and roundness they do so evenly. The particles drop through the spout 62 and out through its mouth 65, falling upon the band of wet paint which has 70 just been deposited on the roadway by the spray 75

gun located in advance of the dispensing device 11.

If the layer of particles deposited is not satisfactory, the operator loosens the screws 58 and moves the slide 59 up or down to widen or narrow the opening between it and the barrier edge 57. In this manner, the correct quantity of particles to be deposited can be accurately regulated. If the spout 62 strikes an obstacle in the road, it merely swings around its pivot screws 63 to avoid the obstacle, returning to its normal position with its upper forward edge resting against the barrier 56 as a stop (Figure 2) under the urge of the tension spring 67.

When the painting is terminated, the operator likewise shifts the lever 38 to open the crown clutch 33, causing the sprocket 24 to rotate loosely upon the shaft 27 and halting the rotation of the feeding blades 51. When this occurs, the feeding of the glass particles through the spout 62 terminates immediately because the edge 57 of the barrier 56 is above the level of the shaft 27, hence above the center of the drum 44. The blades 51 will also serve as baffles in their positions of rest, thereby interfering with the flow of the particles upward over the barrier 56. It will also be observed that the upper edge 57 of the barrier 56 is also at the level of the top of the outlet port 55, which still further impedes the flow of the particles when the blades are not rotating.

It will be further observed that the planes of the blades 51 are not radial but lie in positions between the radial and tangential planes. This positioning of the blades 51 still further enhances the pushing of the particles out of the casing 44 and up the barrier 56.

While the operation of the invention has been discussed in connection with the use of glass particles, it will be evident that it may be used likewise for the dispensing of smooth particles of material such as plastic which also have the properties of rolling over each other with a minimum of friction so as to flow like water over the edge of the barrier 56.

While I have shown and described my invention in detail, it is to be understood that the same is to be limited only by the appended claims, for many changes may be made without departing from the spirit and scope of my invention.

What I claim is:

1. A dispensing vehicle for glass particles or the like, comprising a frame structure, ground wheels mounted on said frame structure, a casing connected to said frame structure and having an inlet and an outlet, a shaft journaled in said casing, a rotor on said shaft in said casing having particle feeding blades thereon, an upwardly-directed barrier connected to said outlet and having an overflow edge positioned for overflow of

said particles thereover in response to the rotation of said rotor, said barrier having its overflow edge positioned above the level of the axis of rotation of said shaft and mechanism drivingly connected to said rotor to rotate said rotor and its blades in a direction upwardly toward said overflow edge of said barrier.

2. A dispensing device for glass particles or the like, comprising a casing having an inlet and an outlet, a shaft journaled in said casing, a rotor on said shaft in said casing having particle-feeding blades thereon, an upwardly-directed barrier connected to said outlet and having an overflow edge positioned for overflow of said particles thereover in response to the rotation of said rotor, said barrier having its overflow edge positioned above the level of the axis of rotation of said shaft and mechanism drivingly connected to said rotor to rotate said rotor and its blades in a direction upwardly toward said overflow edge of said barrier.

3. A dispensing device for glass particles or the like, comprising a casing having an inlet and an outlet, a shaft journaled in said casing, a rotor on said shaft in said casing having particle-feeding blades thereon, a barrier connected to said outlet and having an overflow edge positioned for overflow of said particles thereover in response to the rotation of said rotor, said barrier being inclined upwardly from said outlet and having its overflow edge positioned above the level of the axis of rotation of said shaft, mechanism drivingly connected to said rotor and arranged to rotate said rotor and its blades in a direction upwardly toward said overflow edge of said barrier, and a gate of approximately L-shaped cross-section mounted on said casing above the overflow edge of said barrier and having an upwardly inclined portion approximately co-directional with said upwardly inclined barrier and disposed in spaced relationship therewith.
